—Inventor:
Thomas Crane,
By W. S. Sprague Attys.

UNITED STATES PATENT OFFICE.

THOMAS CRANEY, OF BAY CITY, MICHIGAN.

GRATE.

SPECIFICATION forming part of Letters Patent No. 518,714, dated April 24, 1894.

Application filed January 29, 1894. Serial No. 498,409. (No model.)

To all whom it may concern:

Be it known that I, THOMAS CRANEY, a citizen of the United States, residing at Bay City, in the county of Bay and State of Michigan, have invented certain new and useful Improvements in Grates, of which the following is a specification, reference being had therein to the accompanying drawings.

This invention consists in the peculiar construction of the grate bars, especially designed for burning soft coal whereby the air is fed into the furnace at such points as to give the best effects in combustion. Further in the construction of the grate bars in connection with a hollow bridge or cross-bar at the rear end of the furnace, having apertures in its rear face adapted to supply air for combustion in rear of the grate. Further in the construction of the side grate bars having raised chambers, with perforated rear walls to supply air in the corners wherein the fire is usually slow or dead. Further in the peculiar construction, arrangement and combination of the various parts.

In the drawings, Figure 1 is a plan view of a grate embodying my invention. Fig. 2 is a vertical, central section thereof. Fig. 3 is a detached perspective view of one of the middle grate bars. Fig. 4 is a plan view of a grate bar showing the hollow bridge removed. Fig. 5 is a longitudinal section through one of the end grate bars.

A represents the steam generator and B its setting, provided with the usual air and fuel supply doors at the front and with the bridge wall C at the rear end of the grate.

D is a series of flat grate bars provided with the apertures E and provided on the under side with a rib or web F forming a truss for the central portion of the bar. At the rear end each bar is provided with a hollow passage G leading into a chamber H in a hollow cross-bar or bridge. This cross-bar I may form integral with the grate bars, as shown in Fig. 3, but I prefer to make it detachable,

as shown in Fig. 2, in which case I form a flange I, around each of the passage ways G, and form the bridge in sections, one for each grate bar, adapted to fit over the same. The bridge thus formed consists of the curved front wall a and the inclined rear wall b provided with the inclined apertures c to direct the current of air upward into the line of the products of combustion and toward the bottom of the boiler. The side grate bars I provide at the rear end with section of the bridge and at the forward end with the raised air supply chamber J, formed by the inclined rear wall K and the straight front wall K' supplying air in the corners above the level 60 of the grate, so as to give as good combustion in the corners which are usually dead spaces as in the center or other parts of the grate.

What I claim as my invention is—

1. In a furnace grate, the combination of a series of apertured grate bars, having passage ways G at the rear end of each bar, of the flanges I around such passage ways on the bars, and the hollow bridge wall formed in sections the width of each bar and comprising the curved front wall a and the inclined rear wall b provided with inclined apertures the lower side of the wall being open and fitting around the flanges, substantially as described.

2. In a furnace, the combination of the grate comprising the perforated grate bars, having at their rear ends a hollow raised bridge or cross-bar, having its rear face formed with a series of upwardly inclined perforations, of the side grate bar having a raised air chamber J at their front ends consisting of the rear inclined perforated wall K and the front vertical wall K', substantially as described.

In testimony whereof I affix my signature in presence of two witnesses.

THOMAS CRANEY.
